CIRCULATORY COOLING SYSTEM FOR
INTERNAL COMBUSTION ENGINESWillard L. Morrison, Lake Forest, Ill., assignor
to The Dole Valve Company, Chicago, Ill., a
corporation of Illinois

Application February 19, 1934, Serial No. 711,839

5 Claims. (CL 123—178)

This invention relates to circulatory cooling systems for internal combustion engines and has for its object to provide a new and improved system of this description.

5 When an internal combustion engine is first started up the engine is cold and it is important to heat the engine up as quickly as possible. With the prior circulatory systems the cooling liquid was circulated through the cooling jacket 10 of the engine and the radiator by means of a pump, and a thermostatic valve was arranged in the system to shut off when cold so that when the engine was started up the cooling liquid was held in the cooling jacket of the engine until 15 the temperature was raised sufficiently to cause the thermostat to open and permit the cooling liquid to be circulated through the radiator. This prior system has certain defects, one among others being that when the pump started up the 20 thermostatic valve had to withstand the pressure produced by the pump and sometimes by steam formed in the cooling jacket, and this tends to open the valve.

One of the objects of my invention is to do 25 away with this defect and provide a system whereby the cooling liquid is circulated through a short circuit, including the engine cooling jacket when the engine is cold, and when the temperature of the circulated liquid rises a sufficient amount, the circulation is changed to pass 30 through the radiator as well as the cooling jacket of the engine, and to easily permit the escape of any steam that may be generated. The invention has as a further object to provide a cooling 35 system for internal combustion engine comprising a circulatory system having two branches, one through the radiator and the other short circuiting the radiator, both being opened when the engine is cool, there being thermostatic means for controlling or closing one of the branches 40 when the engine becomes warm. The invention has as a further object to provide a circulatory system with the two branches, the branch through the radiator being open at all times and the branch short circuiting the radiator being arranged 45 so that under ordinary conditions a part of the circulation is through the radiator and a part through the short circuit, the amount through the radiator increasing as the demand for cooling the liquid increases, thereby providing liquid at the proper temperature under all the varying conditions of use. The invention has other objects which are more particularly pointed out in the accompanying description.

Fig. 26 is a view similar to Fig. 25 showing the circulation of the liquid when the engine warms up.

Like numerals refer to like parts throughout the several figures.

Referring now to the drawings, I have shown an internal combustion engine 1 having a cooling jacket. There is a radiator 2 which is provided at the sides with the liquid passageways 3 and 4, and at the top with the passageway 5, and at the bottom with the passageway 6. The passageway 5 communicates with the passageways in the radiator so that the liquid passes from 5 in through the radiator.

In Figures 1 to 10, for example, I have shown a twin block engine having two sets of cylinders side by side. The cooling jacket of one set of cylinders is connected at the bottom by a pipe or connection 7 with the bottom of the radiator, being connected with the passageway 6. The cooling jacket of the block of cylinders on one side is connected by a pipe 8 with the radiator, the connection being made to the passageway 4 intermediate its ends, preferably about the middle thereof. Similar pipes or connections 7a and 8a are made between the other block of cylinders and the radiator, the pipe 7a being preferably connected with the passageway 6 and pipe 8a with the passageway 3. Pumps 9 and 9a are arranged preferably in the pipes or connections 8 and 8a, and these pumps are operated in any suitable manner from the engine.

In the particular construction shown they are operated by a belt 10 run from the engine shaft, this belt also being used to run the fan 11 if desired. Located within the passageway 4 is a valve 12 which is pivotally mounted in position and which closes and opens the port or opening 13. This valve is normally open when the engine is cold and is provided with any suitable thermostatic device 14 which closes the valve when the engine is warmed up.

In the particular construction shown I have illustrated a valve and thermostat support 15 in the passageway 4, and this support also has an opening 16 at the top. Any form of valve or thermostat may be used and I have illustrated an ordinary form of valve and a thermostat made of a coil of two metals of different coefficient of expansion. The passageway 3 has a similar valve and thermostat to that shown in the passageway 4. In this construction when the engine is cold the valves 12 are open. When the engine is started up the pump is operated and the cooling liquid is circulated through a short circuit which consists of the cooling jacket of the engine, the pipe 8, and since the valve 12 is open, the liquid from the pipe 8 passes down through the opening 13 and the lower part 4a of the passageway 4 and the pipe 7 back to the cooling jacket, as shown by the arrows in Figs. 1 and 11. This path of travel of the liquid is insured because of the head of liquid above the valve 12, the liquid taking the path of least resistance which is down through the portion 4a of the passageway 4. It will be seen that this is a comparatively short circuit and that the liquid is not being cooled by the radiator, and hence the cooling liquid will be heated quickly so as to bring the engine up to the proper operating temperature. Furthermore, since there is a circulation of the liquid, instead of the liquid being confined in the cooling jacket, the engine will be uniformly heated as the liquid itself will be uniformly heated due to its circulation. When the engine becomes heated, the

circulating liquid becomes heated and the thermostat 14 acts to partially or entirely close the valve 12, the movement of the thermostat being determined by the temperature of the engine and the liquid. Under ordinary conditions the arrangement will be such that the valve 12 is only partially closed so that a part of the cooling liquid passes through the radiator and a part passes through the short circuit, the two parts mixing at the bottom of the radiator and passing through the pipe 7 into the cooling jacket. The part of the liquid circulated through the radiator will be cooled, while the part circulated through the bypass will not be cooled, and the two mixing will secure a liquid of the proper temperature to secure the most efficient and advantageous conditions. The parts can be arranged so that the short circuit or bypass will only be partially closed, except in the really hot weather, when it may then be fully closed. When the bypass or short circuit is fully closed, the circulation through the bypass will cease and the circulation of the liquid will then be from the cooling jacket of the engine through the pipe 8 upwardly through the passageway 4 into the passageway 5, and thence down through the radiator passageways to the bottom passageway 6, and thence back through pipe 7 to the cooling jacket of the engine, as shown by the arrows in Fig. 12. The circulation through the other side from the other block of cylinders will be similar to that just described.

It will be seen that by this system and apparatus the water is circulated through the short circuit when the engine is first started up so as to insure quick heating of the engine to the proper operating temperature, and then automatically the circulation is changed, part of the liquid going through the radiator so that the liquid may be cooled thereby, and a part of the liquid going through the bypass or short circuit so that it will not be cooled, the two parts being united before or at the time of passing into the cooling jacket so that properly cooled liquid will pass into the cooling jacket to maintain the proper temperature of the engine. It is important that the engine operate at a comparatively high temperature, as it is more efficient when so operated, and it is also important that the temperature shall not be too high.

By means of my invention the temperature is automatically adjusted to the proper temperature by more of the liquid going through the radiator when the temperature rises so as to be cooled thereby, and less going through the radiator when the temperature is lowered, thus automatically securing a proper desired mean temperature for the most efficient operation of the engine. This construction secures substantially the same result as though the size of the radiator was automatically changed in accordance with the demand for its cooling effect. In this construction any steam that may be formed in the circulatory system can easily pass up through the liquid above the bypass and escape without doing damage.

In Figures 13 to 19 inclusive a modified construction is shown. This construction is similar to the construction shown in Figures 1 to 12, except that the valve and thermostat are located in different positions. In this construction the valves 12b are located at the bottom of the passageways 3 and 4 instead of intermediate their ends at the point where the pipes 8 and 8a enter, as in the previously described device. This brings

the valves and the thermostat down into the cross bottom passageway 6 so that the thermostat, instead of being acted upon by the heated liquid immediately after it comes from the cooling jacket, is acted upon by the mixed liquid, a part of which comes directly from the cooling jacket of the engine and part from the radiator after having passed therethrough. It will be seen that this permits the thermostat to be operated at a lower temperature, for this mixed liquid will have a lower temperature than the liquid that comes into contact with the thermostat in Figures 1 to 14.

In this construction the valve and thermostat may be arranged in any desired manner, and I have shown a construction where there is a supporting device 17 which has an opening 18 at the top which is controlled by the valve 12b, and the thermostat 14a is in a position where it is acted upon by the mixed liquid coming down through the passageways 3 and 4 and through the radiator and across the passageway 6 at the bottom through an opening 19 in the supporting device. In the particular construction shown the supporting device has a projection 20 which projects through the wall of the passageway 4 and with which the pipe 7b is connected. The thermostat is mounted in this projecting part 20 and is connected to a lever 21 attached to the valve 12b.

The construction of these parts is set out in detail in Figures 15, 16 and 17. The circulation of the liquid is similar to that heretofore described. When the engine is cold and first started up, for example, the circulation is through the short circuit and is illustrated in Fig. 18, the liquid passing from the engine cooling jacket into the passageway 4 and then down and out through the pipe 7b. When the engine is heated up so as to heat the liquid, the valve 12b is partially or completely closed and the circulation is then partially or wholly upwardly through the passageway 4 and across the top and down through the radiator and then back through the pipe 7b to the cooling jacket, as shown in Fig. 19. In this construction, instead of having two thermostats, it is only necessary to have one, and the other valve on the other side is controlled by a controlling member 22 which extends along the bottom passageway 6 and which connects with the valve 12b on the other side. This cheapens the construction, as it requires only one thermostat to operate the two valves. It also insures the two valves being simultaneously operated.

In Figures 20 to 26 there is shown a further modification adapted to be used in connection with the standard construction of one of the principal automobile manufacturers. In this standard construction the liquid goes from the cooling jacket into a pipe 23 and then through the radiator and back to the cooling jacket through a pipe 24 at the bottom. To apply the present invention to such a construction I provide a connection from the pipe 23 running down to the pipe 24 and arrange the valve and thermostat 25 at the bottom of the pipe 23. One cheap and effective method for securing this result is to provide a coupling member 26, see Figs. 23 and 24, which has an inlet 26 which is connected to the cooling jacket of the engine, and an outlet 27 which is connected with the pipe 23. It has a second outlet 28 which is connected by means of a pipe 29 with the pipe 24. A valve 30 controls the outlet 28 and is arranged so that the outlet is normally opened when the parts are cold. A thermostat 31 is located in the coupling

and is connected with the valve 30. When the engine is started up the liquid being acted upon by the pump passes from the cooling jacket through the inlet 26 into the coupling, and since there is a head of liquid above this coupling, the liquid will take the path of least resistance and will flow down through the outlet 28 into the pipe 29, and thence into the pipe 24 and back into the cooling jacket, thus making a short circuit as indicated by the arrows in Figs. 23 and 25. When the engine is properly heated up the thermostat acts to partially or wholly close the valve 30 and liquid then passes from the cooling jacket into the coupling 25 and then out through the discharge 27 into the pipe 23, and thence across the top 15 into the radiator and down through the radiator and out through the pipe 24 into the cooling jacket, the circulation being indicated by the arrows in Figs. 24 and 26. If the valve is not completely closed, then part of the circulation 20 will be through the bypass or short circuit.

While the invention has been illustrated in connection with the particular construction of automobile, it is of course evident that it may be used with any other form, and I therefore do not 25 limit myself except as set out in the claims hereto appended.

I claim:

1. A cooling system for internal combustion engines, comprising a radiator, an engine cooling jacket, a connecting pipe connecting the lower portion of the radiator with the engine cooling jacket, a connection leading from the engine cooling jacket, a pump in said connection, a pipe leading from said pump connection to the upper 30 portion of the radiator and a pipe leading from said pump connection to the connection between the radiator and the engine cooling jacket.

2. A cooling system for internal combustion engines comprising a radiator, an engine cooling 40 jacket, a substantially vertically extending pipe, having its upper end connected to the radiator and its lower end connected with the engine cooling jacket, a second connection from the engine jacket to said substantially vertically extending pipe intermediate its ends, and a thermostatically controlled valve in said pipe below said latter connection.

3. A cooling system for internal combustion engines, comprising a radiator, an engine cooling 50 jacket, a connecting pipe connecting the lower end of the radiator with the engine cooling jacket, a vertically extending pipe connecting said connecting pipe with the upper end of the radiator, a connection leading from said vertically extending pipe to the engine cooling jacket, a pump in said connection for moving the cooling liquid from the engine cooling jacket into said vertically extending pipe, and means located in said vertically extending pipe for causing the 60 cooling liquid from the engine cooling jacket to pass through one portion of said vertically extending pipe when the engine is cold and through another portion of said vertically extending pipe when the engine is hot. 65

4. A cooling system for internal combustion engines, comprising a radiator, an engine cooling jacket, a connecting pipe connecting the lower end of the radiator with the engine cooling jacket, a vertically extending pipe connecting 70 said connecting pipe with the upper end of the radiator, a connection leading from said vertically extending pipe to the engine cooling jacket, a pump in said connection for moving the cooling liquid from the engine cooling jacket into said 75

vertically extending pipe, and means located in said vertically extending pipe for causing the cooling liquid from the engine cooling jacket to pass through one portion of said vertically extending pipe when the engine is cold and through another portion of said vertically extending pipe when the engine is hot, said means comprising a thermostatically controlled valve located in said vertically extending pipe in proximity to the connection between said vertically extending pipe and the engine cooling jacket.

5. A cooling system for internal combustion engines, comprising a radiator, an engine cooling

Jacket, a connection from the lower end of the radiator to the engine cooling jacket, a vertically extending pipe connecting said connection with the upper part of the radiator, a connection from the engine cooling jacket to said vertically extending pipe, intermediate its upper and lower ends, a pump in said connection, and means for causing the pump to direct the cooling liquid in one direction through said pipe when the engine is cold and in the opposite direction through said pipe when the engine is hot.

WILLARD L. MORRISON.
